UNITED STATES PATENT OFFICE

FRANK FERDINAND JONKEL, OF CHICAGO, AND HOMER WALDO LARSON, OF DOWNTOWN GROVE, ILLINOIS, ASSIGNEES TO WESTERN ELECTRIC COMPANY, INCORPORATED, OF NEW YORK, N. Y., A CORPORATION OF NEW YORK

APPARATUS FOR ARRANGING ARTICLES

Application filed June 16, 1926, Serial No. 116,490. Renewed November 8, 1929.

- This invention relates to apparatus for arranging articles, and more particularly to apparatus for arranging articles in predetermined positions for assembling purposes.
- 5 Where small parts are to be assembled in predetermined positions, it has heretofore been the practice in some instances for a worker to manually select the parts from an indiscriminately arranged supply thereof.
- 10 and then position the parts so selected in predetermined properly arranged positions for assembling. One instance of this practice may be found in the manufacture of heat coils, such as are extensively used in telephone
- 15 systems for protecting the circuits and apparatus from abnormal currents. The outer shell of certain types of these coils comprises a rubber sleeve having a metal cap secured at one end thereof. When assembling these
- 20 shells, it has heretofore been the practice for a worker to manually select a metal cap from an indiscriminately arranged supply thereof and then properly position it for assembling with a companion sleeve portion.
- 25 The principal object of the present invention is to provide a simplified and improved apparatus for effectively and efficiently arranging and magazining articles.
- In accordance with the general features
- 30 of the invention, there is provided in one embodiment thereof a rotatable member having right and left hand spiral grooves formed in separate halves of its peripheral surface and terminating in a common slot or peripheral groove formed in the member substantially midway between its ends, the latter groove being aligned with a magazine designed to receive articles arranged in proper
- 35 predetermined positions. A housing substantially enclosing the rotatable member is designed to hold a supply of promiscuously arranged articles in contact with the peripheral surface of the member.
- 40 Other features and advantages of the invention will become apparent in the following detail description, reference being had to the accompanying drawing, wherein
- 45 Fig. 1 is a plan view, partly broken away, of an apparatus embodying the features of the invention;

Fig. 2 is a vertical section taken on line 2—2 of Fig. 1;

Fig. 3 is a vertical section taken on line 3—3 of Fig. 2, and

Fig. 4 is an enlarged perspective view of 55 an article adapted to be arranged and magazined in a predetermined position by the improved apparatus.

Referring now to the drawing in detail wherein like reference characters designate 60 corresponding parts throughout the several views, the numeral 10 indicates, generally, a horizontally disposed cylindrical screw member having right and left hand spiral grooves 11 and 12, respectively, formed on opposite halves of its outer surface. The adjacent ends of the grooves 11 and 12 terminate in a common slot or semi-circular groove 13 (Fig. 2) formed in the screw member substantially midway between its ends. 70

The screw member 10 is rotatably mounted in frame members 15 and 16, the upper portions of which form opposite side walls of a hopper 17 having front and rear walls 18 and 19, respectively, and designed to hold a supply of promiscuously arranged articles 20 in contact with the screw member 10. Secured at one end of the screw member 10 is a gear 24 meshing with a gear 25 secured to a shaft 26 through which the screw member is driven in the direction indicated by the arrow (Fig. 3) by any suitable source of power (not shown). 75

In the present embodiment of the invention, the articles 20 which are to be arranged in predetermined positions comprise a circular cap portion 21 and an integral cylindrical upset reduced portion 22 (Fig. 4). The spiral grooves 11 and 12 and the semi-circular groove 13 are designed to accommodate the reduced portions 22 of the articles. Disposed in vertical alignment with the groove 13 is a magazine comprising a pair of inverted substantially L-shaped members 28 and 29 secured to a downwardly projecting portion 30 of the front wall 18 of the hopper and spaced therefrom by a plurality of spacing washers 31 so as to accommodate therebetween the portions 21 of the articles when 80 properly positioned as indicated in Fig. 3. 95

100

Vertical portions 32 and 33 of the members 28 and 29, respectively, are parallel to and spaced from each other to form a vertical slot 34 (Fig. 2) which is in alignment with 5 the groove 13 and of such width as to loosely accommodate the reduced portions 22 of the articles.

Horizontal portions 36 and 37 of the members 28 and 29, respectively, are preferably 10 positioned so that the upward edges thereof are disposed slightly below the longitudinal axis of the screw member 10 and suitably spaced from the outer surface of the screw member so as to serve as guide rails for the 15 articles being advanced to the magazine by the spiral grooves 11 and 12. Furthermore, the construction is such that the parts or articles contained in the hopper 17 are prevented from escaping between the screw 20 member 10 and the guide rails 36 and 37. The adjacent ends of the guide rails 36 and 37 slope upwardly towards the slot 34 as indicated at 39 (Fig. 2). This construction prevents any possible jamming when the magazine 25 is full since the articles being advanced along the sloped portions 39 are readily ejected from the grooves in the rotating member 10 upon reaching the magazine slot 34 when this slot is completely loaded.

30 Referring to Fig. 3, it will be noted that the rear wall 19 of the hopper slopes towards the front wall 18 thereof, the lower edge of the rear wall being substantially in vertical alignment with the axis of the screw member 10. This construction of the hopper confines 35 the articles contained therein between the screw member 10 and the front wall 18 of the hopper.

30 In the operation of the above described apparatus, a supply of promiscuously arranged articles are deposited in the hopper 17 in contact with the screw member 10, as shown in Fig. 3. The screw member is then rotated in the direction indicated by the arrow in 45 Fig. 3. It will be obvious that the articles in contact with the rotating screw member will be agitated due to the spiral grooves 11 and 12 thereof, and that some of the articles will become lodged within these grooves and between the wall 18 and the guide rails 36 and 37, as best shown in Fig. 1. Furthermore, any articles so positioned are advanced along the guide rails 36 and 37 into the peripheral groove 13 from which they drop down the 50 vertical slot 34 of the magazine. When the magazine is completely filled, any additional advancing articles are readily ejected from the grooves 11 and 12 upon reaching the peripheral groove 13 due to the sloped portions 39 of the guide rails, as hereinbefore described.

55 Although the invention is herein illustrated and described as particularly applicable for arranging and advancing small parts

employed in heat coils, it should be understood that the novel features thereof are capable of other applications within the scope of the appended claims.

What is claimed is:

1. In an apparatus for arranging articles, a magazine for receiving properly positioned articles, and a member associated with said magazine and having a peripheral groove in alignment therewith, said member having right and left hand spiral grooves terminating in said peripheral groove. 70
2. In an apparatus for arranging articles, a hopper containing a supply of promiscuously arranged articles, a magazine associated therewith for receiving properly positioned articles, and a member having a peripheral groove in alignment with said magazine, said member having right and left hand spiral grooves terminating in said peripheral groove for guiding properly positioned articles thereto. 80
3. In an apparatus for arranging articles, a hopper for holding a supply of indiscriminately arranged articles, a magazine associated therewith for receiving and stacking articles in proper predetermined positions, and a rotatable member mounted within said hopper having a substantially semi-circular peripheral groove for guiding properly positioned articles into said magazine, said member having right and left hand spiral grooves formed on its outer surface for advancing properly positioned article to said peripheral groove. 90
4. In an apparatus for arranging articles, a screw member having a peripheral way for guiding properly positioned articles and oppositely disposed spiral ways terminating in the peripheral way for properly positioning indiscriminately arranged articles and advancing them through the peripheral guideway. 100
5. In an apparatus for arranging articles, a magazine for receiving properly positioned articles, a hopper for containing a supply of indiscriminately arranged articles, and a screw member mounted within the hopper having a peripheral groove for guiding properly positioned articles and oppositely disposed spiral ways terminating in the peripheral groove for properly positioning indiscriminately arranged articles and advancing them through the peripheral groove to 110 said magazine. 115
6. In an apparatus for arranging articles, a screw member having a peripheral groove for guiding properly positioned articles and right and left hand spiral ways terminating in the peripheral groove for properly positioning indiscriminately arranged articles and advancing them through the peripheral groove, and a magazine communicating with 120 125 130

the peripheral groove for receiving properly positioned articles therefrom.

7. In an apparatus for arranging articles, a hopper for containing a supply of indiscriminately arranged articles, and a screw member rotatably mounted therein having a peripheral way for receiving properly positioned articles and oppositely disposed spiral ways terminating in the peripheral way for properly positioning indiscriminately arranged articles and advancing them through said peripheral way.

In witness whereof, we hereunto subscribe our names this 28th day of May A. D., 1926.
